PROCESS FOR MAKING PAVEMENTS AND
THE LIKE

José María Valles Sanchez, Madrid, Spain

Application June 27, 1941, Serial No. 400,007
In Spain July 10, 1940

9 Claims. (Cl. 94—3)

The present invention relates to a process and apparatus for making pavements, the facings of socles, walls and the like, and more particularly to a method and apparatus for laying artificial tile and terrazzo floors, walls and the like containing thin divider strips forming a grid defining mold cavities which are adapted to receive a flowable composition of the same or different textures or colors to form patterns in such facings.

The usual methods of preparing terrazzo floors include assembling a plurality of metallic divider strips into a grid and then filling the grid with a floor surfacing composition. The divider strips are of substantial thickness and are of considerable rigidity inasmuch as they must retain their position and shape while the floor composition is being poured or filled into the pockets or compartments of the grid. Because of the rigidity of such strips, they are not susceptible to any wide variation in their relationship, with the result that the patterns formed with such strips are necessarily limited, unless the strips are preformed into predetermined shapes.

Moreover, unless considerable care is used in the positioning of the strips, the pattern formed by the grid is not uniform and the appearance of the floor suffers.

An object of the present invention is to provide a method and an apparatus for laying divider strips for the facings of walls, floors and the like which assures the accurate positioning of such strips.

Another object of the invention is to provide a method and an apparatus for preparing grids and floorings containing divider strips by means of which a wide variety of patterns may be obtained without the use of preformed divider strips.

Another object of the invention is to provide divider strips which are more economical in use than the strips heretofore used and which are capable of being shaped into a wide variety of patterns.

Other objects of the invention will become apparent from the following disclosure of typical forms of apparatus, methods, divider strips and surface coverings embodying the present invention.

In accordance with the present invention, the facings of floors, walls and the like are prepared by forming a grid of one or more thin, flexible strips or ribbons of metal or other similar material, placing the strip or strips under tension,

and while they are so held under tension, pouring a floor composition into the spaces in the grid, to permit the floor composition to be poured into the grid and allowed to set without distorting the grid.

The strip or strips may be provided with suitable tongues to anchor them in the floor composition and may be notched or slotted to permit the strips to be positioned in intersecting relationships.

Apparatus embodying the present invention includes stretching members adapted to be fixed outside the area to which the flooring or surface covering is to be applied and includes mechanisms for drawing the strips taut and retaining them in fixed position while the floor composition is hardening or setting.

Through the use of my novel divider strips and tensioning apparatus, the strips are rendered rigid and retained firmly in position after they have been positioned in or shaped into the desired pattern. Thus, distortion of the grid is avoided despite the use of divider strips which are sufficiently flexible to be readily bent or flexed into polygonal or other shapes.

For a better understanding of the present invention, reference may be had to the accompanying drawing in which:

Figure 1 is a view in side elevation of a typical form of strip embodying the present invention, disclosing two different forms of tongues struck therefrom for anchoring the strip in the flooring composition;

Figure 2 is a perspective view of a typical form of apparatus for tensioning a plurality of thin, flexible ribbons or strips in the form of a grid;

Figure 3 is a view of a pin and roller construction over which a strip may be drawn to flex it into an angular form; and

Figure 4 is a plan view of a flexible strip positioned in the shape of a parallelogram.

In accordance with the present invention and in the preparation of floors, wall coverings and the like, I form a grid having a plurality of molding cavities F therein from one or more strips 10 of very thin, flexible material, preferably metal.

These flexible metallic ribbons or strips 10 are so thin that they may be bent or flexed into various shapes. These strips 10 may be provided with tongues 11 struck out of the mid-portion of the strip and bent at an angle to the surface thereof, or tongues 12 which may be struck out of the bottom edge of the strip and bent at an angle to the surface thereof. The tongues 12, as illustrated, are of triangular shape, but may

be of any other shape desired, since their function is solely one of positioning and anchoring the strips in the floor composition. Moreover, the strips 10 may be provided with slots 13 spaced predetermined distances apart and extending approximately one-half the width thereof. The function of the slots 13 is to receive other similarly slotted strips so that they may be assembled into a grid G, as shown in Figure 2, with their upper and lower edges in the same plane.

Inasmuch as the strips are thin and flexible, they would not normally remain straight when assembled into a grid formation and, therefore, I have provided mechanism for stretching or tensioning the strips lengthwise to render them sufficiently rigid to be form-retaining.

The stretching or tensioning devices A, illustrated in Figure 2, consist of a channel member 14 supported upon a plurality of legs 15 which are adapted to be positioned outside the area to which the flooring or surfacing is to be applied. The legs 15 may be anchored to the floor or walls in any desired way, such as by screws, so as to retain them in fixed position. Extending through the opposite walls 14a and 14b of the channel member 14 are one or more spindles 16 having slots 16a adjacent their lower ends for receiving the ends of the strips 10.

The slots 16a preferably are so positioned that when the end of a strip 10 is received therein, the inner edge of the strip is spaced slightly from the supporting floor and the outer edge of the strip lies substantially in the plane of the surface of the finished floor. Each spindle 16 is retained against downward movement by means of a ratchet wheel 17 fixed thereto which rests upon the top wall 14a of the channel member 14 and cooperates with a pawl 18 which may be used to retain the spindles against rotation in one direction. A cross-pin 19 forming a handle is provided at the upper end of the spindle 16 so that the spindle may be turned in a direction to wind the end of a strip 10 thereon and place it under tension. Each spindle 16 is retained against upward movement by means of a collar 20 fixed to the spindle 16 and engaging the undersurface of the side wall 14b of the channel member.

As shown in Figure 2, the transverse strips are positioned initially with their ends in the slots 16a of the spindles 16 of the tensioning devices A on opposite sides of the area to which the surfacing composition is to be applied. Likewise, tensioning devices A are positioned at opposite ends of the area to which the surface is to be applied and other strips 10 are so positioned that their ends are received in the slots 16a of the spindles 16 thereof. The longitudinally extending strips may be positioned with the slots 13 opening upwardly and the transversely extending strips 19 may be positioned with the slots 13 opening downwardly so that the strips interfit and form the grid G, disclosed in Figure 2. When the strips are positioned, the spindles 16 are rotated to place the strips under tension and render them rigid. The grid G forms a plurality of cavities which are adapted to receive a floor composition which hardens or sets upon standing. This composition may be of uniform texture and color or varied in color or texture so that when it is deposited in the cavities in the grid a wide variety of patterns may be formed. The grid G, because of the tension on the individual strips, is sufficiently rigid to permit the flooring composition to be poured into the cavities between the strips 10 and allowed to harden therein without dis-

placing the strips 10. After the flooring composition has hardened sufficiently to be self-sustaining, the tensioning devices A are removed from around the area and flooring composition is poured into these vacated areas to complete the floor surface.

While I prefer to form the grid G of a plurality of strips, such a grid may be formed from a single elongated flexible ribbon or strip. As shown in Figures 3 and 4, the strip 10 is wound around a plurality of pegs 21 or pegs 22 having rollers 23 coaxial therewith to form a diamond or other polygonal shape. The inner end of the strip 10, as viewed in Figure 4, is anchored or attached to a stretching device A of the type described above and the other end similarly attached to another stretching device A so that when tension stresses are applied to the strips they will form a figure which is defined by the position of the pegs 21 or peg and roller constructions 22 or 23. Thus, with the single strip it is possible to form any desired design of strips such as parallelograms, polygons or zig-zag formations, as may be desired, utilizing but a single strip of thin, flexible material. After the grid has been formed by tensioning the strip, the flooring composition is poured thereinto as described above. Before the flooring composition has hardened completely, the pegs 21 or 22 and the tensioning devices are removed and the spaces left by removal of these devices are filled with the flooring composition.

The above-described apparatus and process have the advantage of permitting practically unlimited variation in the design formed with the strip or ribbons. Inasmuch as the strips or ribbons are very thin, their cost is relatively less than that of the strips heretofore used with the result that the cost of the floor or wall facings is materially reduced.

While the preferred form of the invention has been described above, it will be understood that other types of strip tensioning means may be used without departing from the invention and that the size and shape of the strip may be varied so long as it is sufficiently flexible to be shaped and positioned by such tensioning means. Therefore, the forms of the invention described above should be considered as illustrative, only, and not as limiting the scope of the following claims.

I claim:

1. An apparatus for forming facings for pavements, floors, walls and the like containing a plurality of angularly related, thin, flexible strips forming molds for receiving initially plastic material which hardens upon standing, comprising means for receiving and positioning one end of each of said strips, means for receiving the other end of each of said strips and means for tensioning said strips to rigidify and position said strips during the application of said plastic material.

2. An apparatus for positioning thin flexible strips to define areas for receiving facing materials which harden upon standing comprising a member adapted to be positioned adjacent one side of an area to which said facing material is to be applied, means on said member for receiving one end of a thin, flexible strip and means for adjusting the first-mentioned means to exert a tensioning stress on said strip to rigidify and position said strip.

3. An apparatus for positioning thin flexible strips to define areas for receiving facing materials which harden upon standing, comprising members adapted to be positioned adjacent opposite sides of an area to which said facing mate-

rial is to be applied, rotatable spindles on said members extending substantially normal to the plane of said area for receiving opposite ends of a thin, flexible strip and means for rotating said spindles to wind the ends of said strips thereon and exert a tensioning stress on said strip to rigidify and position said strip.

4. A method for preparing facings for walls, floors and the like comprising forming at least one flexible, ribbon-like strip into a grid, tensioning said strip to render it rigid and retain it in position, filling said grid substantially to the level of the upper edge of said strip with a plastic composition which hardens on standing and releasing the tension on said strip after the composition has hardened sufficiently to retain the strip in the position assumed by it under tension.

5. A method for preparing facings for walls, floors and the like which comprises assembling a plurality of thin, flexible strips of metal into the form of a grid, tensioning said flexible strips to rigidify and retain them in fixed position, substantially filling said grid with a plastic composition which hardens upon standing and releasing the tension on said strips after said composition has hardened sufficiently to retain the strips in the position assumed by them under tension.

6. A facing for pavements, walls, floors and the like comprising a plurality of angularly related, flexible, tensioned, metallic strips forming a grid defining a plurality of molds, said strips having laterally projecting anchoring means thereon, and a hardened facing material substantially filling said molds and interlocked with said later- 35

ally projecting means to hold said strips under tension, and said strips having edges exposed to view at the surface of said facing.

7. A facing for pavements, walls, floors and the like comprising a support, a plurality of angularly related, flexible, tensioned strips in spaced relation to said support and defining a plurality of mold cavities, a hardened facing material substantially filling said cavities and the space between said strips and said support and holding said strips under tension, and said strips having edges exposed to view at the surface of said facing.

8. A facing for pavements, walls, floors and the like having a flexible, continuous strip of metal embedded therein in a state of lengthwise tension and having an edge portion exposed at the surface of said facing, said strip arranged to define a mold cavity, and a hardened facing material substantially filling said cavity and holding said strip under tension.

9. A facing for pavements, walls, floors and the like having a plurality of flexible, metallic strips embedded therein in a state of tension, said strips each having slots extending in from one edge and spaced at intervals along the length thereof, and being arranged in angularly intersecting relation to one another with the slotted portions in inter-engaging relation, and in their assembled relation forming a grid with a plurality of mold cavities, and a hardened facing material substantially filling said cavities and holding said strips under tension.
